Patented Jan. 11, 1921.

UNITED STATES PATENT OFFICE.

GABRIEL CLARK WILLIAMS, OF BROOKHAVEN, MISSISSIPPI.

BACKBAND-HOOK.

1,365,432.

Specification of Letters Patent. Patented Jan. 11, 1921.

Application filed December 15, 1919. Serial No. 344,829.

To all whom it may concern:

Be it known that I, GABRIEL CLARK WILLIAMS, a citizen of the United States, and a resident of Brookhaven, in the county of 5 Lincoln and State of Mississippi, have invented a new and Improved Backband-Hook, of which the following is a description.

My invention relates to a back band hook 10 and more particularly relates to a back band hook having locking means to engage the trace.

The general object of the invention is to provide a back band hook for the indicated 15 character, improved in various particulars, whereby certain advantages and improved results are obtained, among which are the following:—The hook may be readily applied to back bands of known form; the 20 locking means is of a character to effectively prevent the accidental release of the trace; the hook and its appurtenances are prevented from exerting any rubbing action against the sides of the animal; and provision 25 is made in a novel way for renewing the wear surface against which the trace contacts and the trace may be engaged and disengaged with facility and despatch.

The above and other objects are attained 30 by the novel construction and arrangement of parts hereinafter particularly described and claimed.

Reference is to be had to the accompanying drawings forming a part of this specification it being understood that the drawings are merely illustrative of one example 35 of the invention.

Figure 1 is a front view of a back band hook embodying my invention showing the 40 same applied to a back band shown in part;

Fig. 2 is a transverse vertical section on the line 2—2, Fig. 1;

Fig. 3 is a horizontal section on the line 3—3, Fig. 1;

Fig. 4 is a horizontal section on the line 45 4—4, Fig. 1.

My attachment includes a keeper 10 formed on the lower end of a base plate 11 which is secured by any suitable means to 50 the back band A, as for example, by rivets 12 having washers 13. The keeper is horizontally disposed, preferably approximately round in cross section, and presents a through-passage for the trace B.

55 The hook 14 is vertically disposed on the

front of the base plate 11 and has vertical movement thereon. The hook extends through an opening 15 at the top of the keeper 10 and when in engagement with the trace projects also through a bottom opening 16. At the lower end of the hook 14 is a bill 17 adapted to engage the keeper 10 at a side of the opening 16 and preferably also a shoulder 18 is adapted to engage the top of the keeper adjacent to the front of the top opening 15 so that a double engagement of the keeper is effected. The shank of the hook 14 is secured at its upper end by a transverse pivot 19 extending through ears 19^a on a cross bar 20 of a T-shaped slide 21 60 which has guided movement on the base plate 11. In the illustrated form the engagement of the base plate 11 with the slide is effected by producing forks 22 on the end of the cross bar 20, said forks engaging 65 flat bars 23 formed on the plate 11 at the sides by producing vertical slots 24 therein. Thus the slide 21 and hook 14 may be raised or lowered, for engagement or disengagement of the hook with the trace B 70 when the latter is made to extend through the keeper 10, thereby insuring proper support for the trace and the locking thereof to prevent its accidental loosening.

The hook 14 is subject to a compression 85 spring 25 at the back of said hook, said spring being coiled about a stud 26 projecting forwardly from the base plate 11 and extending into a slot 27 in the shank of the hook. The spring bears at its ends against 90 the base plate and the hook 14 to normally tend to engage the bill 17 and shoulder 18 with the keeper 10. The spring permits of the ready depression of the hook 14 to disengage the members 17 and 18 to permit the 95 upward sliding of the hook for releasing the trace. The upward movement of the hook 14 and its carrying slide 21 is limited, the arrangement being such that with the slide at the extreme upper ends of the guide 100 bars 23, the hook will be so positioned that its bill 17 engages the top of the keeper 10 at the opening 15, thereby preventing the hook from complete disengagement from the keeper.

In order that the surface at the interior of the keeper, subject to the wear of the trace B, may be readily renewed, I produce a lining 28 detachably held in the keeper by suitable means, there being shown for 110

the purpose end lugs 29 which are bendable to engage or disengage the ends of the keeper 10.

I would state in conclusion that while 5 the illustrated example constitutes a practical embodiment of my invention, I do not limit myself strictly to the mechanical details herein illustrated, since manifestly the 10 same can be considerably varied without departure from the spirit of the invention as defined in the appended claims.

Having thus described my invention, I claim as new, and desire to secure by Letters Patent:

15 1. A back band attachment including a keeper having a through-passage for a trace, and a hook slideable transversely of said passage to engage or disengage the trace, and pivoted to have lateral swinging movement into or out of latching engagement with said keeper.

20 2. A back band attachment including a keeper having a through-passage for a trace, and a hook slideable transversely of said passage to engage or disengage the trace, and pivoted to have lateral swinging movement into or out of latching engagement with said keeper; together with spring 25 means acting on said hook and tending to maintain the same in latched engagement with the keeper.

30 3. A back band attachment including a base plate attachable to a back band, a keeper integral with said plate and horizontally disposed, said keeper presenting a through-passage for a trace and having openings in the top and bottom thereof, a hook slideable on said base plate and extending 35 through the top opening of the keeper and

movable to a position to extend also through 40 the bottom opening to thereby extend across the passage of the keeper for engaging a trace, said hook being pivoted to have lateral movement in the openings into and out of latched engagement with the keeper, and 45 spring means acting on said hook, and tending to maintain the same in latching engagement with the keeper.

4. A back band attachment including a keeper presenting a through-passage for a 50 trace, a hook pivoted to swing transversely of the keeper for engaging the same and slideable to or from a position extending across said passage for engaging the trace, said keeper having top and bottom openings to accommodate the hook, members on 55 said hook positioned to engage the keeper at the respective openings when the hook is in position across the passage, spring means tending to maintain the hook in 60 latched engagement with the keeper, and means limiting the sliding movement of the hook in one direction so that when the hook is in the released position one of the members thereof will engage the keeper 65 adjacent to the top opening, and when in the locking position said member will be positioned for engaging the keeper at the bottom opening.

5. A back band device including a keeper 70 through which the trace may be passed, and a hook slideable on said device longitudinally thereof, at the inner side of said keeper and movable transversely into or out of engagement with the keeper to engage or dis- 75 engage a trace.

GABRIEL CLARK WILLIAMS.
